TAPE RECORDER DECK

Howard R. Cederberg and William C. Bortzfield, Tulsa,
Okla., assignors to Midwestern Instruments, Inc., Tulsa,
Okla., a corporation of Oklahoma

Filed Jan. 27, 1964, Ser. No. 78,369

Term of patent 14 years

(Cl. D26—14)

Fig. 1.

Fig. 2.

Fig. 3.

Fig. 4.

FIGURE 1 is a front perspective view of a tape recorder deck showing our new design;

FIGURE 2 is an end elevational view thereof;

FIGURE 3 is a front perspective view of a tape recorder deck showing a modified form of the present invention; and

FIGURE 4 is a top plan view of the tape recorder deck shown in FIGURES 1 and 2.

The dominant features of the design reside in the portions shown in full lines.

We claim:

The ornamental design for a tape recorder deck, substantially as shown and described.
